ISAIAH NUTT, OF NEW YORK, N. Y.

Letters Patent No. 91,478, dated June 15, 1869.

IMPROVED MACHINE FOR REFITTING CONICAL VALVES.

The Schedule referred to in these Letters Patent and making part of the same.

To all whom it may concern:

Be it known that I, ISAIAH NUTT, of the city, county, and State of New York, have invented a new and useful Improvement in Machines for Refitting Valves, of which the following is a full, clear, and exact description, reference being had to the accompanying drawing, forming part of this specification, and in which—

Figure 1 represents a partly sectional plan of a machine for refitting valves, constructed in accordance with my invention, and

Figure 2, a side elevation of the same.

Similar letters of reference indicate corresponding parts.

This improvement relates to machines for refitting stop and other like valves of conical character; and

The invention consists in a combination, with a stationary concave rest or guide to the valve and adjustable centre, of a sliding cutter, arranged so as to be capable of feed through a slot in the concave, for action in or against the valve, as the latter is rotated within the concave.

Referring to the accompanying drawing—

A represents the frame of the machine, which is made to carry, at its one end, a stationary concave rest or guide, B, the same being a hollow cone made smooth on its interior, and having a longitudinal slot, a, cut through it on the one side, which slot may extend the length of the cone, or thereabouts.

The other end of the frame carries an adjustable centre, C, which is arranged in line with the centre of the concave, and which serves, in connection with the concave, to centre and hold the valve D to be refitted, as represented in fig. 1, the bearing-portion, s, of the valve, or the valve proper, as it may be termed, resting on and being guided by the smooth interior surface of the stationary concave B.

Rotary motion is communicated to the valve by a ratchet-brace applied to the adjustable centre, through a fork connecting the latter with the valve, or in any other suitable manner, and said valve, whilst being rotated, borne up against the interior of the concave.

E is the cutter, which may either be straight or concave on its cutting-edge, and, lying loosely on a support, F, is projected through the slot a, in the concave,

up against the valve, by means of a lever, G, with which said cutter may gear through a pin, b, on its face, being made to fit or enter any one of a series of notches c, in the lever, according to the diameter of the valve to be operated on; but such adjustment is, or may be dispensed with, where the edge of the valve s is straight, instead of convex, and the cutter, having a straight cutting-edge, be constructed to extend the full length of the slot a, or thereabouts.

In such latter case, said cutter, by reason of the length of its cutting-nose or end, will answer for various diameters of valves without adjustment along the support F, and, as it is important that its cutting-edge should at all times be in line or parallel to the side of the concave B, it projects through or into, it may be guided in its feed up against the valve, by setting it to slide within a recess in the support F, as indicated by red lines in fig. 1, or it may be otherwise suitably guided.

From this description, it will be seen, that while the valve is at once readily adjusted to insure its being refitted true, it is both guided and supported by the smooth interior surface of the stationary concave B. This is in no way analogous to a revolving concave mill, which necessitates the use of an additional centre, and presents several cutting-edges that cannot be sharpened, to suit different-shaped edges to the valve, as can a single detachable cutter as employed in this my machine.

Such previous machines, in fact, have not been adapted to refit valves of a rounded form on their edge, for which form of valve my invention is particularly applicable.

What is here claimed and desired to be secured by Letters Patent, is—

The combination, with the adjustable centre C, and stationary concave B, constructed smooth on its interior, to form a rest and guide for the valve, of the sliding cutter E, arranged to project through a slot, a, in the concave, substantially as specified.

ISAIAH NUTT.
